AXEL G. BERGMAN, OF NEW YORK, N. Y., ASSIGNOR TO ORDNANCE ENGINEERING CORPORATION, OF NEW YORK, N. Y., A CORPORATION OF NEW YORK.

ILLUMINATING-BODY.

1,381,445.

Specification of Letters Patent. Patented June 14, 1921.

Application filed July 12, 1919. Serial No. 310,464.

To all whom it may concern:

Be it known that I, AXEL G. BERGMAN, a subject of the King of Sweden, residing in borough of Manhattan, city, county, and 5 State of New York, have invented certain new and useful Improvements in Illuminating-Bodies, of which the following is a specification.

The present invention provides an improved gun projectile, of the "star" or illuminating type, and improved elements of said projectile; particularly the illuminating body, and an igniting body for said illuminating body, of especial utility in the 15 case of projectiles containing illuminating bodies of a construction and composition which render them of difficult ignition. The present type of shell carries an illuminating charge which is usually in the form of a 20 mass of brilliantly burning material, and the composition of which usually includes magnesium in some form. The illuminating body which I prefer to use is made under heavy compression, from two tons upward 25 to the square inch, this compression having for its purpose to enable the illuminating body to withstand the shock of being fired from a gun, to insure the most efficiency as regards the duration, intensity and 30 regularity of burning, and to render the illuminating composition less susceptible to impregnation by moisture.

According to certain of my prior inventions, I am enabled to provide a projectile which is capable of use in high powered or rifled guns, so that illumination may be effected considerable distances away from the gun, and some form of timing mechanism is adopted, by which the illuminant 40 will function at various points in the trajectory of the shell, means being provided for checking the velocity of the illuminant at the time when it is desired that it shall function, and means being also provided for sustaining the illuminant in the air after 45 ignition, and the projectile of the present invention preferably includes appropriate features of my said prior inventions.

In this type of projectile, especially, the 50 muzzle velocity is usually very high, ranging from 2,800 to 3,200 feet per second. While this velocity falls during the travel of the projectile, it is found that in most cases when the illuminant is ignited, the latter

still maintains a very rapid rate of travel, 55 which is maintained for a short time after the functioning of the igniting means until the illuminating body has been checked. Shells or projectiles of this type are shown for instance in Patents Nos. 1,305,186, 60 1,305,187, and 1,305,188, granted to me on May 27, 1919.

In order to assist in the ignition of the illuminant composition, it has been proposed to include in the end of the illuminating shell 65 or star a plug or pellet which is composed of quick burning powder, and which is exposed at one end to the flame of the igniting charge. Such plugs have been made in cylindrical form, but have been found unsatisfactory for the purpose, due probably to the fact that the excessive draft caused by the rapid movement of the illuminant through the air draws or sucks the products of combustion of the igniting pellet rearwardly through the opening, so that insufficient heat is developed against the contiguous 75 walls of the illuminant to properly ignite it.

According to the present invention, the 80 illuminating body is provided with an embedded or included ignition body or pellet, which ignition body or pellet is preferably overhung by portions of the illuminating body, and is further preferably characterized by the fact that its interior cross-section 85 is greater than its cross-section at the point where it passes out to the outer wall of the star. Or in other words, the construction is such that the exit opening for 90 the gases of the pellet is restricted in area, so that such gases are maintained in contact with the contiguous wall of the star a sufficient length of time to insure ignition of the latter.

In the drawing, wherein I have shown one form of the invention,

Figure 1 is an elevation, partly in longitudinal section, of an illuminating body or star of cylindrical form, containing my improved igniting pellet.

Fig. 2 is a plan view of the pellet itself.

Referring to the drawing, let A indicate the star which is formed of a suitable composition and which I prefer to construct according to the method hereinafter described. Embedded in the rear or igniting end of the illuminant is the pellet or body B, the end

of which C extends to the rear end D of the star, or is otherwise exposed to an igniting flame.

According to the present invention the pellet or body B is preferably of such shape that its interior cross-section is greater than its exterior cross-section where it emerges from the body of the composition. In the particular construction illustrated the pellet is shown as being of substantially frustoconical shape with a cylindrical base E.

In constructing the pellet, I prefer to use meal powder or fuse powder and to compress this powder to a very high pressure. I have found that admirable results are obtained if the pressure approximates fifteen tons per square inch. The pellet may have any suitable composition, however, but care should be taken that its composition is such that it will not explode. The purpose and effect of subjecting the pellet or igniting body to this great pressure is to reduce the time of burning of the powder or other material of which it is composed, so that the combustion is changed from an ordinary flash to a distinct interval of time, approximating two to three seconds, thus providing for a sustained combustion of the igniting body against the contiguous walls of the illuminating body.

One practical means of introducing the pellet into the star is to mold it in during the molding of the star, the entire structure according to the present invention being preferably placed under about five tons' pressure during the molding operation. For this purpose the particular construction of igniting pellet illustrated is of importance since it has no weak points which might be disrupted during the heavy pressing operation. It also has no thin flanges or portions which might be broken off either before or during the molding operation.

It is desirable that the end C of the pellet where it emerges from the star shall be clean and bright, in order that it may certainly become ignited, and for this purpose I prefer to drill a small hole G which may be of conical shape in the end of the pellet before the star is loaded in the shell. I have also found it desirable to face the end of the star with a very light covering of blasting powder, which is indicated by the letter H, which, however, is best applied before the drilling operation just described.

In loading the shell or projectile it will be understood that the igniting charge is placed next to or communicating with the layer of blasting powder or the end of the pellet.

Upon the functioning of the time fuse the igniting charge of the shell is fired, and the pellet or igniting body B is thereby ignited. The latter burns but does not flash and generates a high temperature, and the gases of combustion seek to rush out of the ex-

terior opening in the star, but because of the restricted diameter of this opening as compared with the bulk of the pellet or the overhang of portions of the illuminating body, they are retained in intimate contact with the contiguous walls of the star a sufficient length of time to insure the certain ignition of the star. Moreover, the igniting body preferably extends for a considerable depth into the illuminating material, thus assuring that the walls of the illuminating body will be wiped by the flames from said igniting body in passing outward. As here shown, the igniting body extends a distance nearly twice its diameter into the illuminating body.

The pellet may be of various shapes other than that shown without departing from the invention. I have described this feature of the invention with reference to the shape of the pellet because of the fact that in practice the pellet is usually constructed first and the walls of the star which surround it take their shape from that of the pellet. It will be understood, however, that this feature of the invention may be regarded as comprising the formation of a star or similar body with a recess having a restricted orifice, in which recess an igniting composition is placed. Preferably this orifice is formed in the composition of the star itself. For the best results, the restriction must be effected by the closing in of the composition to be ignited, so that there will be an angular, rather than a substantially parallel, contact between the flame and the composition to be ignited.

This feature of the invention is applicable to other devices than that indicated, and may be employed under any circumstances which demand a practically certain ignition of a more difficultly ignitable body under severe conditions.

In constructing the illuminant or star, I preferably use barium nitrate and potassium nitrate, magnesium powder, and aluminum powder. These are mixed warm with paraffin and the mass is then compressed under high pressure, preferably about five tons per inch. I have found in practice that it is very important in the manufacture of such stars that the barium, aluminum and magnesium be in a state which is thoroughly dry. By this I do not mean what is ordinarily regarded as dry in the sense of being free from perceptible moisture, since I have found that the unexplained failure of many previous illuminants to ignite has been due to a slight degree of moisture, such as would be the result of handling or mixing the several chemicals in a room where there was a percentage of humidity of perhaps forty-five or fifty degrees or over. Such chemicals have heretofore been believed to be substantially non-

absorbent, and the humidity of the mixing room has not heretofore been thought to have any effect upon the igniting or burning qualities of the illuminant.

5 According to my invention I mix the several chemicals employed, or other suitable chemicals, under conditions where the humidity does not exceed forty-five per cent. and preferably where it is less than thirty-
10 five per cent. As a matter of practice before mixing I thoroughly dry the ingredients so as to make certain that they have no excess moisture. While the ingredients are in this dry state, they are mixed with paraffin, which while commonly used as a binder has the additional effect of preventing the ingredients from absorbing moisture, if afterward brought into contact with moist air. The use of paraffin in the case of what may
15 20 be described as moist ingredients has had precisely the contrary effect in the past, since it prevented any possible evaporation of such moisture.

What I claim is:—

25 1. A projectile adapted to be discharged from a gun, and having therein a "star" mass or body, and means for igniting said star mass or body while in flight, said means comprising an igniting body embedded in said star mass or body, and having a face adapted to be exposed to an igniting flame, and means for restricting the flow of gases out of the cavity produced by the progressive burning of said igniting body, whereby the rarefaction behind said mass produced by the rapid flight thereof is prevented from affecting the combustion of said igniting body to an extent that will interfere with its action in igniting said star mass.

60

3. A projectile adapted to be discharged from a gun, and having therein a "star" mass or body, and means for igniting said star mass or body while in flight, said means comprising an igniting body embedded in said star mass or body, and having a face adapted to be exposed to an igniting flame, said igniting body being reduced, at its ex-

posed end, and said star mass having a portion overhanging said reduced portion, whereby the flame from said igniting body is caused to wipe the overhanging portion of said star mass, and whereby the rarefaction behind said mass, produced by the rapid flight thereof, is prevented from affecting the combustion of said igniting body to an extent that will interfere with its action in igniting said star mass.
70
75

4. A projectile adapted to be discharged from a gun, and having therein a "star" mass or body, and means for igniting said star mass or body while in flight, said means comprising an igniting body embedded in said star mass or body, and having a face adapted to be exposed to an igniting flame, said igniting body being generally conical in shape, and having its smaller end outermost, and said star mass having a portion of corresponding shape overhanging the said igniting body in a manner to restrict the flow of gases out of the cavity produced by the progressive burning of said igniting body, whereby the flame from said igniting body is caused to wipe the overhanging portion of said star mass, and whereby the rarefaction behind said mass, produced by the rapid flight thereof, is prevented from affecting the combustion of said igniting body to an extent that will interfere with its action in igniting said star mass.

85
90
95

5. A projectile adapted to be discharged from a gun, and having therein a "star" mass or body, and means for igniting said star mass or body while in flight, said means comprising an igniting body embedded in said star mass or body, and having a face adapted to be exposed to an igniting flame, and means for restricting the flow of gases out of the cavity produced by the progressive burning of said igniting body, whereby the rarefaction behind said mass, produced by the rapid flight thereof, is prevented from affecting the combustion of said igniting body to an extent that will interfere with its action in igniting said star mass. said igniting body having a relatively large area of contact with the star mass along an axis running inwardly of said igniting body.
100
105
110
115

6. A projectile adapted to be discharged from a gun, and having therein a "star" mass or body, and means for igniting said star mass or body while in flight, said means comprising an igniting body embedded in said star mass or body, and having a face adapted to be exposed to an igniting flame, and means for restricting the flow of gases out of the cavity produced by the progressive burning of said igniting body, whereby the rarefaction behind said mass, produced by the rapid flight thereof, is prevented from affecting the combustion of said igniting body to an extent that will interfere with its action in igniting said star mass.
120
125
130

1. with its action in igniting said star mass, said igniting body having a length in the star mass along an axis inwardly thereof approximating or exceeding its breadth.
2. 7. A projectile adapted to be discharged from a gun, and having therein a "star" mass or body, and means for igniting said star mass or body while in flight, said means comprising an igniting body embedded in said star mass or body, and having a face adapted to be exposed to an igniting flame, and means for restricting the flow of gases out of the cavity produced by the progressive burning of said igniting body, whereby the rarefaction behind said mass, produced by the rapid flight thereof, is prevented from affecting the combustion of said igniting body to an extent that will interfere with its action in igniting said star mass, said igniting body being formed under pressure sufficiently high to reduce its combustion from a flash to an enduring flame.
3. 8. A projectile adapted to be discharged from a gun, and having therein a "star" mass or body, and means for igniting said star mass or body while in flight, said means comprising an igniting body embedded in said star mass or body, and having a face adapted to be exposed to an igniting flame, and means for restricting the flow of gases out of the cavity produced by the progressive burning of said igniting body, whereby the rarefaction behind said mass, produced by the rapid flight thereof, is prevented from affecting the combustion of said igniting body to an extent that will interfere with its action in igniting said star mass, said igniting body being formed under pressure sufficiently high to reduce its combustion from a flash to an enduring flame, 15 tons per square inch being a representative pressure in the case of gun powder.
4. 9. A projectile adapted to be discharged from a gun, and having therein a "star" mass or body, and means for igniting said star mass or body while in flight, said means comprising an igniting body embedded in said star mass or body, and having a face adapted to be exposed to an igniting flame, and means for restricting the flow of gases out of the cavity produced by the progressive burning of said igniting body, whereby the rarefaction behind said mass, produced by the rapid flight thereof, is prevented from affecting the combustion of said igniting body to an extent that will interfere with its action in igniting said star mass or body being compressed so as to materially reduce the power of absorption of moisture by said mass.
5. 10. An igniting body or pellet, composed of a rapid burning material, and compressed under a representative pressure of 15 tons per square inch, whereby to prolong the time of burning thereof from a flash to the order of a second, said body having a generally conical shape.
6. 11. A star or illuminating mass or body, adapted to be projected from a gun as a part of a projectile or shell, adapted to be ignited in rapid flight, comprising an igniting body embedded in said star mass or body, having a face adapted to be exposed to an igniting flame, and means for restricting the flow of gases out of the cavity produced by the progressive burning of said igniting body, whereby the rarefaction behind said mass, produced by the rapid flight thereof, is prevented from affecting the combustion of said igniting body in a manner that will interfere with its action in igniting said star mass.
7. 12. A star or illuminating mass or body, adapted to be projected from a gun as a part of a projectile or shell, and adapted to be ignited in rapid flight, comprising an igniting body embedded in said star mass or body, and having a face adapted to be exposed to an igniting flame, said star mass having a portion overhanging said igniting body.
8. 13. A star or illuminating mass or body, adapted to be projected from a gun as a part of a projectile or shell, and adapted to be ignited in rapid flight, comprising an igniting body embedded in said star mass or body, and having a face adapted to be exposed to an igniting flame, said igniting body being reduced at its exposed end, and said star mass having a portion overhanging said reduced portion.
9. 14. A star or illuminating mass or body, adapted to be projected from a gun as a part of a projectile or shell, and adapted to be ignited in rapid flight, comprising an igniting body embedded in said star mass or body, and having a face adapted to be exposed to an igniting flame, said igniting body being generally conical in shape.
10. In witness whereof, I have hereunto signed my name.
- AXEL G. BERGMAN.
